UNITED STATES PATENT OFFICE

CHARLES LEONARD PETERS, OF LONDON, ENGLAND, ASSIGNOR TO SIEMENS BROTHERS & COMPANY, LIMITED, OF LONDON, ENGLAND

TELEPHONE SYSTEM

Application filed March 20, 1930, Serial No. 437,544, and in Great Britain March 26, 1929.

The present invention relates to automatic and semi-automatic telephone systems and more particularly to a system employing register controllers for recording the numbers 5 dialled by subscribers and controlling selection of the desired line and for other operations connected with the setting up of a call.

The invention though capable of wider applications is especially suitable for use in connection with small unattended exchanges and meets the demand for special services. The system shown herein may be considered as an improvement on the system shown in the patent to D. A. Christian, 1,738,564, 15 granted December 10, 1929.

It is provided in the present invention that a digit recording switch in the register controller or an equivalent of such switch e. g. a relay set hereinafter called a digit switch 20 has more contact positions than those corresponding to the digits employed in the subscriber numbering scheme, and the surplus contact positions are employed for special operations to be controlled by a distant operator. Such special operations include trunk 25 offering whereby the entry into an engaged line must be secured, getting access to a tone circuit which can signify a normal or abnormal condition at the exchange and controlling the starting or stopping of battery charging equipment.

The special operations are initiated by the operator dialling a digit or digits which sets the digit switch onto the appropriate contact 35 where an appropriate relay may be operated.

A further feature of the invention is that to prevent any interference by ordinary subscribers, the relays concerned with the special operations are only connected to the switch 40 contacts when the register controller is taken into use by an operator. To this end it may be arranged that whilst the incoming end of the junction from the operator's position has line equipment such as is provided for a subscriber's line, certain auxiliary equipment is 45 provided whereby a relay is operated in the register controller and connects up the relays concerned with the special operations. If connections are made to the surplus contacts 50 whereby an ordinary subscriber may by dial-

ling special digits bring about certain operations such as the setting up of a connection to the manual operator or a throw-out of exchange apparatus on interparty calls, these special digits may be used by an operator for other purposes by providing for a change of connections when the relay operated from the auxiliary equipment is energized. 55

Likewise if provision is made whereby a signal is given to a subscriber if he dials a digit not in the range of subscribers' members, the surplus contacts involved or any of them may be used for special operations controlled by the operator. 60

In connection with trunk offering it may be provided that the operator dials a special first digit to bring about circuit changes in the register controller of which allow of breaking into an existing connection. 65

In this case we may arrange that the first digit switch of the register controller after being operated by the special first digit causes a discriminating relay to operate and then returns to normal to be operated subsequently by the first digit of the subscriber's number. 70

In a system in which the testing of a required subscriber's line and the subsequent operations are effected from the register controller, the discriminating relay may control circuit for switching through the operator to the required subscriber's line independently of whether the line is free or busy. 75 80

Where the register controller includes an additional switch or switches which are operated to select a ringing circuit for party line calls, one of the switches may also be used to select circuits for say battery charging control under the control of impulses sent by the operator, the first digit sent having operated a "special operation" relay which brings the ringing circuit selecting switch into the impulsive circuit. 85 90

Other features of the invention will become apparent upon a further perusal of the specification. 95

Reference will now be had to the accompanying drawings which show by way of example one method of carrying out the invention. The drawings show circuits in a small unattended automatic telephone ex- 100

change in which provision is made for local calls between individual line subscribers, calls to and from party line subscribers, and calls over junctions between the automatic exchange and an operator's position at a main exchange. Besides the handling of ordinary subscriber calls, the operator at the main exchange is able to set up trunk calls to a subscriber who is already engaged in a local call, and to control the charging of the battery at the automatic exchange and to ascertain if any faults exist at the automatic exchange and if so the class of fault.

For the purpose of the following description the drawings should be arranged with Figs. 1, 2 and 3 on the left, Fig. 4 to the right of Figs. 2 and 3, and Figs. 5 and 6 beneath one another below Fig. 4. Fig. 7 should be placed on the right of Fig. 4.

Fig. 1 shows equipment connected in between the line circuit shown in Fig. 2 and the terminals on the main distributing frame connected to a junction to the main exchange which controls the special services provided for. The line circuit shown in Fig. 2 may be used in connection with subscribers' lines or with junction lines, the straps shown on the left of the figure being removed when the circuit is connected to equipment as shown in Fig. 1. Fig. 3 shows an assigner for allotting, for use on a call, one of two register controllers which connects itself to an idle connecting circuit and receives the dialled impulses, sets the connector of the connecting circuit on to contacts associated with the required line and performs any special services as will appear later. The connecting circuit and the circuits of one register controller are shown in Figs. 4, 5 and 6, the connecting circuit being shown in Fig. 4 together with a switch in the register controller for selecting a free connecting circuit and associating the register controller with it. Fig. 7 is a line circuit which is similar to that shown in Fig. 2 and shows the connection to the connector multiple banks which have been omitted from Fig. 2 for the sake of convenience.

An outline of the general operation of the exchange apparatus in setting up a call will first be given after which will follow a more detailed description of the circuits involved and of those concerned with the performance of the special services available to an operator at the main exchange.

On the initiation of a call, the line relay LA operates and closes a circuit to the assigner AC which then assigns a free register controller to deal with the call. A hunting switch CCF is set in motion to connect the register controller with a free connecting circuit CC, the call finder CF of which proceeds to search for the calling line which when found is connected over the banks of the switch CCF to the register controller.

In the register controller are three digit

switches DT, DU and DA on which the digits of the subscriber's number are recorded. The exchange in the present example is arranged for 50 lines, consequently individual subscribers' numbers will comprise two digits only and these are recorded on switches DT and DU. DA records the digit which designates a particular party on a party line and provides for the application of the appropriate ringing code, the control of the code ringing being effected by switch DB. Switch DA is also employed in connection with the control of the charging of the automatic exchange battery. Switches DT, DU, DA are 25-point switches, and as regards switches DT and DU, the operative contacts in the first part of their banks are connected symmetrically to contacts in the latter part of their banks. Only some of these contacts are required for subscribers' numbers, the remainder being used for special purposes. For instance in the arrangement shown contacts 2 to 6 from the normal in the banks of switch DT are allotted to subscribers' numbers; contacts 1 and 8 are wired for dealing with dead number calls; contact 7 is wired for the release of the exchange apparatus on interparty calls, in which case, before the calling subscriber uses his hand generator to call the wanted party on the same line, he dials the digit 7 to effect the release of the seized exchange apparatus. Contact 9 of switch DT is wired for fault supervisory purposes and for the control of the battery charge while contact 10 is used for outgoing junction calls from a subscriber and for the setting up of preferred calls to a busy line by an operator at a distant exchange. This latter operation and those giving the special services provided for over contact 9 can only take place when the call is initiated by an operator at a distant exchange as the relevant circuits depend for their operation on the energization of relay JC which can only occur when the register controller is connected over the junction equipment jumpered in between the main distributing frame and the line circuit.

The switch CCF besides hunting for a free connecting circuit acts as a sequence switch with three positions. In the first position an idle connecting circuit is seized and its call finder rotated in search of the calling line. When this has been found the switch CCF is stepped to its second position and the dialled digits are received in the register controller on the digit switches. When all the digits have been received the wanted line is marked in the bank of the connector CS which is started in search of the marked line. The line when found is tested to ascertain whether it is free or busy and if free is marked engaged against other call finders and connectors. The switch CCF is then stepped to its third position in which ring-

ing current is connected to the line from the register controller and on the reply of the called subscriber, the ringing is tripped and the speaking wires are switched through in the connecting circuit, the subscriber's meter is operated, and the register controller is released.

As outline having been given of the operations involved in the case of an ordinary call, the various circuit operations will now be considered in greater detail.

For the purpose of the following description of the setting up of calls from a subscriber connected to the automatic exchange, Figs. 2 to 7 should be arranged as before described. As regards Fig. 2 the straps between the terminals will remain as shown, the meter M being connected to wire d. Wires a and b are connected to the subscriber's line on the main distributing frame.

When a subscriber lifts his receiver to make a call his line is looped and line relay LA operates over the loop. At contact la1 the test-in circuit of the connector CS (Fig. 4) is opened thereby marking the line engaged in the connector multiple. This can be seen by reference to Fig. 7. In its front position contact la1 connects battery over cut-off relay CO and back contact pg2 to the test bank contact of the call finder CF (Fig. 4) to mark the line as calling in the call finder banks. At contact la2 a circuit is closed for relay AS in the assigner. Relay PG is included in this circuit but does not operate owing to the resistance of the circuit.

If the assigner circuits are in the position shown a circuit for relay AA is closed from battery over contact bb2, winding 1 of relay AA, back contacts bb1, cc1, contact as1 to earth. Relay AA operates and at contact aa4 closes a circuit from battery over winding 1 of relay CC, back contact bb4, front contact aa4, contact as1 to earth. Relay CC operates and at the front position of its make-before-break contact cc1, connects earth over contact as1, winding II of relay CC and front contact aa3 to the starting wire of a register controller, which wire is either connected to battery over starting relay ST if the register controller is free, or is disconnected if the register controller is engaged. If the register controller is free, relay CC holds in series with relay ST. Relay BB operates by means of its winding I in series with winding I of relay AA and contact aa2 when the short circuit across it is removed by the changing over of contact cc1 and opens contact bb2. Contact bb1 changes over leaving the two relays dependent on relay AA. If the register controller assigned over the front of contact aa3 is busy, relay CC does not hold and on the restoration of contact cc1, winding II of relay BB energizes over contacts bb3, bb1, cc1 and as1. At the same time winding II of relay AA is energized in parallel with

winding II of relay BB and as the windings of AA are arranged differentially, the latter relay releases and contact aa1 and aa2 opening, leave relay BB dependent on relay CC for its continued energization. Contact aa4 falling back closes a circuit for winding I of relay CC over the front of contact bb4 and winding II of relay CC is connected over back contact aa3 to the other register controller, two register controllers being provided. When contact cc1 changes over relay BB releases and opens the circuit of winding I of relay CC leaving that relay dependent on the condition found on the wire connected to the back of contact aa3. If the register controller, the starting relay of which is connected to this wire is free, relay CC continues to hold otherwise it releases and relay AA re-operates to test the first-mentioned starting circuit again.

Assuming that one of the register controllers is free, relay ST operates in a circuit from battery over the relay winding, contact tr2 of the ring tripping relay TR, contacts q1, d7, wiper DT5 of the "tens" digit switch in its normal position, contact aa3, winding II of relay CC, contacts cc1 and as1 to earth.

Switch CCF besides connecting the register controller to the connecting circuit acts as a sequence switch for the carrying out of various operations through the connecting circuit under the control of apparatus situated in the register controller. For this purpose the switch has three positions associated with a connecting circuit. In the first, the test for a free connecting circuit is made, the call finder set hunting for the calling line and the line extended to the register controller. In the second, the dialled impulses are received and the connector set on to the wanted line, and in the third, the called line is rung, and when the subscriber replies to the call, the calling subscriber's meter is operated. The switch remains in the third position after use in which position the test circuit over wiper 7 of switch CCF is either open or earthed. On the closure of contact st2 a circuit is closed for magnet DF over an interrupter and the switch is stepped once to the first position associated with another connecting circuit. If this circuit is busy the test relay T associated with switch CCF will either be short circuited over wiper 7 and contact v1 in the other register controller or the circuit of relay T will be open at contact vv7 in the engaged connecting circuit. Switch CCF is stepped by the interrupter until a free circuit is found. Whilst in the second and third positions associated with an engaged connecting circuit, relay T will be prevented from operating in a similar manner to that in the first position.

The circuit of relay T being prepared at contact st1 the relay operates when free contacts are encountered over wiper 7 in its first

position, contacts tc_2 and vv_7 in the connecting circuit to battery. Contact st_3 closes a circuit for relay TP to set in motion a switch for releasing the register controller if a connection is not completed within a prescribed period. Contact st_5 closes a holding circuit for relay ST against operation of relay Q.

When relay T operates contact z_1 short circuits the high resistance winding I of the test relay T to reduce the potential on the testing contact to mark the connecting circuit engaged. Winding I of relay Q is energized over contact t_2 and the relay operates slowly. Contact t_3 changes over to prepare the circuit of magnet DF for stepping the switch to its second position. Contact t_4 prepares the circuit of the call finder test relay TC, contact t_5 prepares a circuit for relay B and contact t_6 operates magnet DC of the connector. Magnets DF, DA and DB are all of the reverse-drive type, i. e., they step their switches on the release of their armatures. Relay Q operating contact q_4 opens the circuit of magnet DC and the connector takes one step.

Contact q_1 opens in the operating circuit of relay ST but this relay is held over contact st_5 . A circuit is now closed from earth over interrupter contacts q_3 , b_5 , q_2 , wiper 5 of switch CCF in its first position and contact tc_3 , magnet DD of the call finder to battery. The call finder CF is stepped in search of the calling line unless it happens to be standing on contacts connected therewith at the time. When the calling line contacts are reached, relay TC operates in a circuit from earth over contact t_4 , wiper 2 of switch CCF, its winding I, wiper C of the call finder, contacts pg_2 , la_1 in the line circuit, relay CO to battery. Contact tc_2 changes over to connect winding II of relay TC in a holding circuit in series with winding II of relay T and in parallel with relay S. Contact tc_1 connects earth to the call finder test wiper to mark the line engaged and to operate relay CO which locks up over its contact co_1 . Contacts co_2 and co_3 disconnect line relay LA and on its release, relay PG operates over contacts la_2 and co_4 but without effect. Contact tc_3 opens the call finder magnet circuit and contacts tc_4 , and tc_5 connect the incoming speaking wires to the bank contacts of wipers 1 and 3 of CCF. Relay B having operated, the windings I and II of relay A are connected to wipers 1 and 3, and that relay operates.

Contact b_6 opens a point in the interrupter circuit for magnet DF and contact b_4 closing operates this magnet over front contact t_3 . Contact b_7 operates the slow releasing dialling relay D via wiper DT2 and its normal bank contact. Relay A operates over the subscriber's loop in the circuit traced and at contact a_2 operates relay V.

Relay V operating contact v_1 short circuits

relay T which thereupon releases and at contact t_3 opens the circuit of magnet DF causing it to release and step switch CCF to its second position. Relay Q is released at contact t_2 and contact q_1 closes in the operating circuit of relay ST, which circuit however, is now open at contact d_7 which released relay ST when relay D operated. The register controller cannot now be assigned by an assigner as the circuit over contact aa_3 and winding II of relay CC is open. Other effects of the operation of relay V are the retention of the circuit of relay TP over contact v_3 , the preparation of a circuit for relay SA at contact v_2 , the preparation of a holding circuit during impulsion for relay D at contact v_4 and of an impulsion circuit for the digit switch magnets DT and DU at contact v_6 . Contact v_5 closes a holding circuit for relay B. Contacts d_2 and d_3 opens points in the circuits of slow releasing relays G and E, contact d_4 prepares the impulsion circuit of the digit switch magnets, and contacts d_5 opens the circuit over wiper DT6.

On the operation of relay B a dialling signal is applied to the line over wire DS, contact to_5 , normal bank contact and wiper DT4, condenser, contact b_2 , wiper 1 of CCF and contact tc_4 and the subscriber commences to dial the number of the wanted subscriber which, except in the case of a party line subscriber, comprises two digits. The numbers 20 to 69 are allotted to subscribers in the present example and the circuit operations applicable to a call to one of these numbers other than one allotted to a party line subscriber will first be followed.

The dialled impulses take effect on relay A which repeats them to the digit switches at contact a_2 , the impulses of the first digit being repeated over contacts a_2 , v_6 , d_4 and g_4 to magnet DT. Switch DT is stepped in accordance with the number of impulses received and its wipers DT3 and DT6 are brought to one of the contacts 2 to 6, counting the normal contact as 0. The operating circuit of relay D is opened at the end of the first impulse at wiper DT2 and the relay is then dependent on back contact a_1 for its continued energization. The dialling signal is cut off at wiper DT4 and the starting circuit is further opened at wiper DT5. At the end of the impulse train relay A remains steadily operated and relay D releases. Relay G now operates from earth over contact b_7 , wiper and commoned contacts 1 to 10 in the bank of wiper DT2, contacts s_1 and d_2 , and locks up over contact g_1 . Contact g_4 substitutes magnet DU for magnet DT for the reception of the units digit. A circuit is also closed from earth over contacts v_4 , a_1 , g_2 , n_1 , jt_1 , wiper DU7 and normal contact for relay D which re-operates and again prepares the impulsion circuit. Contact g_3 closes a point in the circuit of the test relay P for testing the called

line, contact g_5 opens a point in the busy signal circuit and contact g_6 prepares a circuit for operating magnet DF. The units train of impulses is now dialled and is repeated to magnet DU which steps the switch in accordance with the number of impulses received and wipers DU2-6 are brought to contacts connected to the marking bank associated with wiper D of the connector.

5 At the end of the units train of impulses, relay D releases and a circuit is closed from earth over contacts v_4 , a_1 , g_2 , n_1 , j_1 , wiper DU7 and common contacts, contacts d_3 , 7_4 , contact e_5 on the other register controller 10 available over the assigner via wires e , contact r_6 , relay E to battery.

15 It may here be noted that should the second register controller be in use at this time, confusion in the banks of the connectors might 20 occur should the banks be marked over contact e_4 and wiper DT3 and one of the banks of switch DU at this time. If the called line marked by the second register controller has not yet been found, its relay E shown in 25 dotted lines at E¹ at the bottom of Fig. 6 would be operated and its contact corresponding to e_5 would be open thereby delaying 30 operation of relay E.

As soon as the other calling line is found 35 and tested relay E¹ releases and its contact e_5 completes the circuits of relay E which thereupon operates and locks up over contact e_1 independently of contact a_1 . Contact e_5 opens to prevent operation of relay E¹ in the 40 other register controller at this time. Contact e_2 closes a circuit from earth over the interrupter, contacts s_3 , e_2 , b_3 , b_5 , wiper r of CCF, magnet DC of the connector to battery and the connector wipers are stepped round 45 the bank.

50 Contact e_4 marks the called line in the bank of wiper D of the connector, the line marked depending on the position of the wipers of switches DT and DU, and contact e_3 prepares a circuit for relay S, which circuit is closed when the connector wipers reach the marked line. The connector is stepped until its wiper D is brought to the marked contact whereupon the following circuit is 55 closed: earth over contact e_4 , wiper DT3 and its bank contact, one of the wipers DU2-6 depending on the position of switch DT, wire 11, bank contact and wiper D of the connector, bank contact and wiper 8 of CCF in position 2, contact e_3 , relay S, winding I, to battery. Relay S operates and at contact s_3 opens the stepping circuit of the connector magnet. At contact s_1 relay S locks up over its winding II and contact b_7 to earth and 60 opens the circuit of relay G. Contact s_2 closes the circuit for test relay P over wiper 6 of CCF and wiper C of the connector. A test of the called line is now made during the release period of relay G, the circuit being 65 from earth over contacts g_3 , s_2 , windings I

and II of relay P, wiper 6 of CCF, wiper C of CS, contact l_1 , (Fig. 7), relay CO to battery. If the line be free relay P operates and short circuits its high resistance winding I 70 over contacts p_1 and b_1 and connects earth thereover for holding by means of its winding II and for reducing the potential of the test bank contact in the connector to mark the line engaged. Contact p_4 closes energizing magnet DF of switch CCF. 75

Consequent on the release of relay G which now takes place, contact g_6 opens the circuit of magnet DF which releases and steps switch CCF to its third position. Relay E 80 releases consequent on the opening of contact g_2 and at contacts e_2 and e_3 , a circuit is closed for ringing the called subscriber. This circuit is over the ringing generator RG, contacts r_4 , p_2 , e_3 , wiper 8 of CCF in position 3, contact vv_4 in the connecting circuit, connector wiper B, the called loop, wiper A of the connector, contact vv_3 , wiper r of CCF, contacts b_5 , b_3 , e_2 , p_5 , r_5 , winding I of relay TR to battery. At the same time a ringing signal is transmitted to the calling 90 subscriber over wire RS, contacts r_3 , p_3 , d_6 , b_2 , n_3 , b_2 and wiper 1 of CCF. 95

When the called subscriber replies relay TR operates by means of its winding I in the above-traced circuit and locks up over its winding II and contacts tr_1 in series with relay Q, winding II, contact v_4 to earth. Contacts tr_3 and q_6 connect battery over contacts tr_2 and s_6 , wiper 4 of CF and D of CF, subscriber's meter M (Fig. 2) to earth and the call is metered against the calling subscriber. Contacts tr_2 and q_1 open in the circuit of relay ST and contacts tr_4 and q_5 connect earth over wiper 2 of CCF to relay 100 VV in the connecting circuit to operate it. At contacts vv_1 - vv_4 the speaking circuit is switched through and current is fed to the calling line over relay YA and to the called line over relay YY and the register controller 105 is disconnected from the called line side of the feeding bridge. Contacts vv_5 and vv_6 connect earth to the test wipers of the call 110 finder and connector respectively of the connecting circuit, the latter contact short circuiting relay P, and contact vv_7 opens the holding circuit of relay TC. Relays YA and YY operate and close a holding circuit for relay VV and contact yy_2 connects earth to wiper D of CF and conversation ensues. 115

Consequent on the release of relay TC by 120 the opening of contact vv_7 relay A in the register controller releases followed shortly by relay V. When relay V releases, earth over the front of contact v_4 is disconnected and relays TR and Q releases slowly. Relay B is released at contact v_5 , relay TP at contact v_3 and relay SA at contact v_2 . Relay S is released at contact b_7 and contacts b_2 and b_3 open further points in the circuit 125 of relay A. Over the back of contact v_4 a circuit 130

cuit is closed for driving the digit switches to their normal positions. The "units" switch is first restored, its magnet DU self-stepping in a circuit including self-interrupting contact *du*, wiper DU1 and contact *v4* and when this switch reaches its normal position its stepping circuit is opened and a similar circuit for switch DT is closed over wiper DT1 and normal contact in the bank of wiper 6 DU1, the circuit being opened when the "tens" switch reaches its normal position. When this occurs the circuit of relay ST is closed at wiper DT5 and all the other relays having 10 released, the register controller is free for use 15 on the next call.

At the end of the conversation, relay VV is released when either of the subscribers replaces his receiver, and earth being disconnected from the test wipers of CF and CS, 20 relays CC in the two line circuits release. Should one of the subscribers fail to replace his receiver, his line relay LA operates on the release of relay CO and relay PG being slow in releasing is held over contacts *la2* 25 and *pg1* until the subscriber's loop is opened. The line tests busy so long as this condition persists by the disconnection of the connector test circuit at contact *la1* whilst battery over relay CO and contacts *la1* and *pg2* operates a 30 high resistance relay for starting a delayed alarm device.

If when the called line is tested, it is found busy relay P does not operate and on the release of relay G, a busy signal is transmitted to the calling subscriber over wire BS, 35 contacts *s4*, *g5*, *p3*, *d6*, *l2*, *n3*, *b2* and wiper 1 of CCF.

It will now be assumed that an individual line subscriber wishes to make a call to another subscriber who is one of a number connected to a party line. The numbers of party line subscribers contain 3 digits, the first two digits representing the line in the exchange numbering scheme, the third digit 40 being a digit for the selection of the appropriate ringing code for calling the party desired. The first digit of party line subscribers is 4 and contact 4 in the bank of wiper DT6 is connected to wiper DU8, contacts of 45 which associated with party lines are commoned and connected to relay R which brings about circuit changes for preventing the connection of ringing current after the end of the second impulse train and for the selection 50 of the appropriate ringing code.

The call proceeds in the manner above described until the end of the second train of impulses. The "tens" digit switch has been set to the fourth contact in its banks and the 55 "units" switch to one of the contacts commoned and connected to relay R. When relay D releases at the end of the second impulse train, a circuit is closed from earth over contacts *v4*, *d5*, wiper DT6 and fourth contact, wiper DT8, commoned contacts to relay

R and battery. Relay R operates and at contact *r1* closes a circuit for relay RD over wipers DA1 and DB1. Relay RD operates and prepares a holding circuit for itself at contact *rd1* by which it holds during the subsequent impulse train. Contact *r2* prepares a circuit for magnet DA of the code selecting switch. Contact *r4* disconnects the ringing generator which provides the interrupted ringing current for ordinary subscribers' lines and prepares a circuit for the application to the called line of code ringing current; contact *r3* disconnects the ordinary ringing signal circuit over wire RS. Contact *r5* disconnects relay TR from the ringing circuit and closes an alternative return circuit for the ringing current. Contact *r6* 70 opens the circuit of relay E until the third train of impulses is dialled thereby preventing the stepping of the connector should the calling subscriber delay or omit to dial the third digit. The receipt of the third digit by relay A is repeated to magnet DA in the following circuit:—earth over contacts *a2*, *v6*, *d4*, *rd4*, *r2*, magnet DA to battery. Contact *a3* 75 holds relay RD during the receipt of the impulse train. Switch DA is provided with 6 wipers and corresponding banks of which wipers DA2 and DA3 are directly concerned with the ringing of the particular party required. The bank contacts of wiper DA3 are connected to wipers DB2—DB6 of a switch DB to which reference will shortly be made whilst the even contacts of wiper DA2 are commoned and connected to certain contacts in banks DB2—6 and to relay RR, the wiper DA2 itself being connected to certain other contacts in the banks of switch DB prior to those which determine the end of a 80 ringing code period.

When switch DA is stepped from its normal position relay E is re-operated, and closes the circuit for the connector driving magnet which steps the connector to the contacts of the required line marked over wiper DT3 and one of the wipers DU2—6 and the usual test is made. On the release of relay RD at the end of the third digit and assuming for the moment the line to be free, an interrupter is connected over contacts *n5* and *rd2*, wiper *da5*, front contact *p6* of the test relay P, magnet DB to battery. Magnet DB is energized intermittently to step the wipers DB1—6 and after a few steps a circuit is closed from earth over contact *rd3*, wiper DA3, one of the wipers DB2—6, relay RR to battery. This is the commencement of the code ringing period. Relay RR operates and at contact *rr1* connects the continuous ringing generator over front contact R4 and wiper 8 of CCF in position 3 to the called line while contact *rr2* connects a tone over wire DS. contacts *p3*, *d6*, *l2*, *n3*, wiper 1 of CCF to the calling line to provide a ringing signal similar to the code to be transmitted. 90

As switch DB is stepped, relay RR is intermittently operated depending on its connections to the bank of switch DB and the particular bank of that switch in use. It will be noticed that each wiper of the set DB2-6 is connected to consecutive pairs of contacts in the bank of wiper DA3 so that as far as this wiper is concerned the same code would be sent out for two positions of the code selecting switch DA. However, in order to distinguish between the digits represented by a pair of contacts in the bank of wiper DA3, a wiper DA2 and bank are employed, the even contacts only in this bank being utilized. 5

10 Wiper DA2 is connected to contacts in the banks of switch DB immediately before those which determine the end of the code and the commoned even contacts are connected to relay RR so that for even "third" 15 digits, an extra ring is included in the code. When the whole code has been transmitted, switch DB is stepped on to the commoned contacts in the latter part of its bank connected to relay RT which thereupon operates 20 and remains operated until the switch reaches its normal position. A circuit is now prepared for relay TR as follows:—earth, winding I of relay TR, contacts $r2$, $r5$, $p5$, $e2$, $b3$, $b5$ wiper 5 of CCF in position 3, contact $vv3$, 25 30 the called line wires, contact $vv4$, wiper 8 of CCF, contacts $e3$, $p2$, $r4$, rl , $rt1$, to battery. This circuit is prepared at the end of each code ringing period and when the subscriber replies to the call relay TR operates 35 and locks up and in conjunction with relay Q brings about the switching through of the connection. Contact $vv6$ short circuits relay P which releases and at contact $p6$ opens the stepping circuits of switch DB and closes a 40 circuit for its rapid return to normal should it not have reached this position. In the normal position of switch DB a homing circuit for switch DA is prepared.

Following on the switching through of the 45 connection, the register controller is released and on the release of relay V the "units" and "tens" digit switches are restored in turn.

The disconnection of earth over front contact $v4$ releases relay R and the homing circuit 50 for switch DA is closed over contact $r2$, self-interrupting contact da , wipers DA1 and DB1, and switch DA is stepped to its normal position. The register controller circuits are now all in their normal conditions and 55 the apparatus may again be taken into use.

If the called line is busy when tested relay P does not operate and switch DB is not stepped so that ringing current is not applied to the line. The calling subscriber receives 60 a busy signal as in the case of a call to a busy individual line.

When a call is originated by a party line subscriber the procedure is similar to that described for a call by an individual subscriber.

65 If a party line subscriber desires to call

another party on the same line, he proceeds as follows:—

On removing the receiver from its hook and on receipt of the dialling signal, the subscriber dials the digit 7, after which, and with the receiver still off, he uses the hand magneto generator provided with the instrument for calling the party required, manipulating it so as to apply ringing current on to the line in accordance with the code of the required subscriber. 70 75

When the receiver is first lifted, a free register controller at the automatic exchange is taken into use and the dialling signal is connected to the calling line when it has been found by the call finder CF. The digit 7 is received by relay A and switch DT is stepped to its seventh bank contact. At the end of the impulse train, relay D releases and earth over contacts $v4$ and $d5$ and wiper DT6 is connected to relay RL, which thereupon operates and locks up over contact $rl3$ independently of switch DT. Contact $rl1$ connects battery over a high resistance and wiper 4 of CCF to wire d in the line circuit which in the case of a party line has an auxiliary equipment as before mentioned connected between it and the main distributing frame. A relay in this equipment connects earth to wire c to hold relays CO and PG operated and to disconnect the line circuit from the assigner and to mark the line engaged in the connector multiple, this earth connection being extended over contact $co1$ to the test bank contacts in the call finders. Contact $rl2$ opens the holding 80 85 90 circuit of relay B which in turn releases relays A and V and the register controller circuits are restored to their normal condition. 95

The engaged marking is maintained for the duration of the call and is controlled by the auxiliary equipment referred to. When both parties replace their receivers, this earth is removed, relays CO and PG release and the line circuit reverts to its normal condition. It may be noted that although relay PG is 100 105 operated, there is no circuit over contact $pg2$ to the alarm relay circuit due to relay LA being unoperated.

The system provides for the connection of small private branch exchanges and those are called in the same manner as an individual line by dialling the number of the first of the group of lines connected to the P. B. X. If this line be busy, the connector proceeds to hunt over the P. B. X. group in search of a free line. In order that all the lines of a P. B. X. shall be marked when a call to one is made, the appropriate bank contacts of switch DU are commoned and the corresponding marking wires 11 are connected to the bank contacts of wiper D of the connector over a break contact $pg3$ shown in Fig. 7, the dotted line connection being removed except in the case of the last line of the group when the strap is retained, as whatever the condi- 115 120 125 130

tion of the last line of the group, the connector must be stopped thereon. As the operation of the connector is that of a hunting switch searching for a marked line, it will be realized that switch CS will be stepped until a marked line is reached. If any of the lines of the group other than the last are busy, the marking in the bank of wiper D of the connector will not be present owing to the marking circuit being open at contact *pg3*, relay PG being operated consequent on the operation of the cut-off relay CO, and the connector will be stepped on until a marked contact is reached. Should all the lines of a P. B. X. group be busy, the connector is stopped on the last contact of the group as this contact is always marked, the contact *pg3* of the line circuit being short circuited by the strap.

If any group of ten lines is not connected, such as the groups having first digits 1 and 8 in the present example, the corresponding contact in the bank of wiper DT6 is connected to a relay L. If any individual line *i* in a group is not connected, the corresponding contacts in the bank of wiper C of the connectors, are connected to wire 13 which is also connected to relay L in the register controller when relay E is operated. If, now, either the digit 1 or 8 be dialled as the "tens" digit, relay L operates by means of its winding I on the release of relay D and locks up over contacts *l1* and *v4*. Contact *l4* opens preventing operation of relay E, and contact *l2* connects a distinctive tone signal over wire NU, contact *n3*, wiper 1 of CCF to the calling line to notify the calling subscriber that he has called a "dead" number. Should the "tens" digit be correct, but the whole number represent a "dead" line, relay L is not connected over wiper DT6. At the end of the second train of impulses, relay E operates and at contact *e6* battery over winding II of relay L is connected via wire 13 to the multiplied contacts in the bank of wiper C of the connector, the usual marking circuit being completed over wire 11. When the marked line is reached, relay S operates and connects relay P in the test circuit, but owing to the high resistance of windings II of relay L, relay P does not operate but relay L does. Contact *l1* closes a locking circuit over winding I of relay L and contact *l3* opens in the stepping circuit of the connector while switch CCF is in its second position. The "distinctive" tone is connected to the calling line at contact *l2*.

Consideration will now be given to calls made over a junction between the automatic exchange and a manual operator at a main exchange. The auxiliary equipment shown in Fig. 1 is connected between the junction terminals on the main distributing frame and the line circuit, Fig. 2, and Fig. 1 must be assumed to be now connected to the left

of the line circuit shown in Fig. 2. The strap connecting wire *c1* from the connector multiple and wire *c* from relay CO is disconnected and meter M is disconnected from wire *d* in Fig. 2. Wires *c* and *c1* are now joined through the low resistance winding I of relay JS and wire *d* is connected to winding II of relay JS in the auxiliary equipment.

There may be junctions to only one main exchange or to more than one. In the first case, a subscriber wishing to make a call over a junction, dials the single digit "0". In the second case he dials the digit "0" followed by another digit signifying the particular group of junctions required. As regards the connector circuit, arrangements similar to those described for a P. B. X. are provided to enable the connector to be stepped to the first junction in the group and to search the group for a free junction and to stop on the last line of the group if all the others be engaged. Relay JT is connected to the tenth contact in the bank of wiper DT6 and when there is only one junction group the tenth contact in the bank of wiper DT3 is connected via wires 12 and 11 to the contacts corresponding to the junctions in the marking bank of the connector in a manner similar to the described for P. B. X. lines. When there is more than one junction group the tenth contact in the bank of wiper DT3 is disconnected from wire 12 and connected to one of the wipers DU2-6 depending on the "tens" group in which it is desired to connect the junctions.

When there is only one group of junctions, a subscriber wishing to make a call over a junction dials the single digit "0" and at the end of the impulse train relay JT operates over its winding I and wiper DT6. Relay G operates and earth over contacts *v4*, *a1*, *g2*, *n1*, front contact *jt1*, contacts *d3*, *l4*, wires *e*, contact *v6*, is extended to relay E which thereupon operates instead of awaiting the end of a second train of impulses. The strap across back contact *jt1* shown in dotted lines is removed so that relay D does not re-operate on the closure of contact *g2*.

Consequent on the operation of relay E the connector is stepped in search of a free junction and when one is found, relay S operates via the connector marking bank, wire 12, and wiper DT3. Relay P operates over wiper C of the connector, winding I of relay JS (Fig. 1) and relay CO in the line circuit and switch CCF is stepped to its third position where ringing current is applied to the junction. Relays JS and CO operate, the latter extending earth first over the low resistance winding of relay P and later over contact *vv6*, the connector wiper C and bank contact, contacts *l1* and *c1* in the line circuit to the test bank contacts of the call finders to mark the line engaged in the fall finder banks. Relay JR

130

operates but neither it nor relay JS serve any useful function at this stage. On the operation of relay JT contact $jt2$ opens the metering circuit to prevent metering on junction 5 calls and prepares a locking circuit for winding II of relay JT when the operator replies to the call. At the end of the conversation when the calling subscriber replaces his receiver, relays YA and VV in the connecting 10 circuit CC release and contact $vv6$ opens the circuit of relay JS releasing it and relay CC. Relay LA is re-connected to the junction in the line circuit and during the release period of relay JR, the current in the junction is 15 reversed thereby giving a clearing signal to the operator.

If there is more than one junction group, the back contact $jt1$ is short circuited by the strap shown in dotted lines and the connection 20 of the tenth contact in the bank of wiper DT3 is made as above described. The subscriber dials the requisite digits to reach the exchange desired and at the end of the first train, relay D releases and operates relay JT. 25 At the same time relay G operates and on the closure of contact $g2$ relay D re-operates over normal contact and wiper DU7, the strap across the back of contact $jt1$, contacts $n1$, $g2$, $a1$, and $v4$, and opens the circuit of relay 30 E before this relay has time to operate in a circuit including the front of contact $jt1$. The second digit is now dialled and at the end of the impulse train, relay E operates and search for a junction in the marked 35 group by the connector takes place.

Consideration will now be given to calls made by a manual operator over the junction to a subscriber on the automatic exchange, after which the various special 40 services available only to an operator will be dealt with.

An operator at the main exchange desiring to make a call to the automatic exchange inserts a calling plug into the junction jack 45 thereby operating relay LA over a loop closed in the cord circuit. The assigner allots a free register controller to deal with the call and the register controller hunts for and seizes a free connecting circuit and the associated call finder is rotated in search of the 50 calling junction. When this is found the register controller and switch CCF is stepped from its first to its second position. Relay B operates when the junction is found and 55 a circuit is now closed from earth over contact $b1$, winding I of relay JC, contacts $to2$, $rl1$, $s6$, wiper 4 of CCF, wiper D of the call finder, wire d winding II of relay JS to battery. Relay JC which is of high resistance 60 operates but relay JS does not. At contact $jt1$ a locking circuit is prepared for winding II of relay JC, this circuit being closed on receipt of the first impulse of the "tens" digit train. It will be noted that relay JC 65 can only operate on calls made by an op-

erator over a junction as in the case of subscriber initiated calls, wire d is earthed over the meter M. The operator receiver dialling signal and the connection is set up in the manner described for calls made by a 70 subscriber. When the called subscriber replies relay YY operates and at contact $yy2$ connects a comparatively low resistance earth to wiper D of the call finder and relay JS operates. Contact $js1$ operates relay JR to 75 prepare for the giving of the ring-off signal. When the called subscriber clears relay YY releases and at contact $yy2$ releases relay JS. Contact $js1$ opens the circuit of relay JR, but this relay being slow to release 80 a period occurs when, with relay JS released and relay JR operated, a reversal of current in the junction wires takes place which operates the clearing indicator at the main exchange. Current is cut off the junction 85 on the subsequent release of relay VV.

If the operator wishes to offer a trunk call to an engaged subscriber, the junction is extended through a free connecting circuit to a register controller and relay JC is operated. 90 Contact $jc3$ disconnects relay JT and prepares a circuit for relay TO.

The operator on receiving dialling signal 95 dials the directory number of the wanted subscriber prefixed by the digit "0". At the end of the last impulse of the first train of impulses representing the digit "0", relay TO operates over wiper DT6 and locks up over its contact $to1$ and contact $v4$, and relay JC locks up over its winding II and wiper DT2, 100 the circuit over its winding I being opened at contact $to2$. Contact $to5$ opens the dialling signal circuit. A circuit is now closed from earth over contacts $jc2$, $to3$, wiper DU1 and normal contact, wiper DT1 and commoned contacts, self-interrupting contact dt , magnet DT to battery. Switch DT self-steps to normal whereupon the locking circuit of relay JC is opened at wiper DT2. Relay TO 105 remains held. The remaining digits representing the subscriber's directory number are now dialled and the connector searches for the line marked in its marking bank. When this is reached relay S operates and the test circuit is closed at contact $s2$ in the usual way. At the same time, relay VV in the connecting circuit is operated from earth over contacts $s5$ and $to4$, and wiper 2 of CCF in position 2. Contact $vv6$ short circuits relay P and relay 110 TC is released at contact $vv7$ thereby initiating release of the register controller. The connection is switched through and as the called subscriber is already engaged in a connection, relay YY will operate round the loop 115 which is already closed. The operator can speak to the wanted party and request him to clear the connection and await the offered trunk call. Contact $yy2$ operates relay JS and when the wanted party clears, a clearing signal is received by the operator. She then 120

125 can only operate on calls made by an op-

clears the connection in order to release relay PG which locked up when relay CO was released at the connecting circuit and sets up a new connection, this time dialling 5 the directory number without the prefix "0".

If the operator desires to ascertain whether a fault exists in the automatic exchange or, if a fault has been previously signalled, whether it still persists, she dials the single 10 digit "9". The register controller being taken into use by an operator, relay JC is operated and at contact jc4 relay N is connected to the ninth contact in the bank of wiper DT6 in place of relay L. At the end of the impulse 15 train relay N operates and at contact n3 connects the fault tone lead FT over wiper DA6 and normal contacts at each end of its bank, and wiper 1 of CCF to the line so that the operator receives a tone denoting the type 20 of fault existing, assuming there to be one.

It may be noted that should a subscriber dial "9" as a first digit, relay L will operate over wiper DT6, bank contact 9 and back contact jc4 and he will receive the dead number 25 tone.

By dialling certain numbers, the operator can control the charging of the battery at the automatic exchange and ascertain by means of a tone signal the state of charge of the battery. This being another service available 30 to operators only, its operation is made dependent on the energization of relay JC. To ascertain if charging is in progress the operator dials "93". To start charging she 35 dials "95" and to stop the charge "97". On receipt of the digit 9, relay N operates and at contact n2 operates relay R which in turn operates relay RD. Contact n1 opens to prevent re-operation of relay D and operation 40 of relay E and contact n5 disconnects the interrupter from wiper DA5 to guard against any possible stepping of switch DB. The second train comprising 3, 5 or 7, impulses is dialled and is repeated in a circuit from 45 earth over contacts a2, v6, d4 rd4, r2 to magnet DA and switch DA is stepped accordingly. At the end of the impulse train, relay RD which is held during impulsing over contacts a3 and rd1, releases and winding III 50 of relay D is connected over contacts rd5 and n4 and wiper DA6 to the appropriate lead. If the second digit is "3" a tone is transmitted over the lead connected to contact 3 in the bank of wiper DA6 to winding III of relay 55 A and the tone is induced in the windings I and II of this relay and thence over the junction to the operator's position. If the second digit be "5" or "7" earth over winding III 60 of relay A operates the relay to effect the required operation. Relay A is not held by this winding owing to the resistance of the circuit in which it is included. The register controller is released by the withdrawal of the plug from the junction jack by the operator.

65 Brief reference will now be made to the

arrangements provided for releasing the register controller if it is not otherwise released within a prescribed time.

When the register controller is taken into use relay ST operates and at contact st3 closes a circuit for relay TP, the circuit being maintained after the calling line has been found by the call finder by contact v3. Relay TB operates and starts up a timing device and earth is connected to wire 14, thence over contacts 70 sa1 and v2 to relay SA. Relay SA operates and locks up over contact sa1 and at contact sa2 connects relay ZA to wire 15. After the elapse of a prescribed time interval and if relay V has not yet been released earth is 75 connected to wire 15 and relay ZA operates and locks up over contact za1. Contact za2 opens the holding circuit of relay B which releases and by releasing relay A initiates the release of the register controller. Relay 80 SA is unlocked on the release of relay V and opens the locking circuit of relay AZ.

If a fault develops on a subscriber's line or a subscriber fails to clear after a conversation, or his line is otherwise looped, relay CO 85 is released either by relay VV in the connecting circuit or by the forced release of the register controller and relay LA re-operating, relay PG remains held. A circuit is then closed from battery over relay CO, contacts la1 and pg2 for relay PL which is of 90 high enough resistance to prevent operation of relay CO and after the elapse of a prescribed interval, an alarm relay is operated. The operated condition of this relay may be 95 ascertained by means of a tone signal connected to a junction in consequence of an operator dialling the digit "9" to ascertain if a fault exists.

What is claimed is:

1. In a register controller arranged to control the setting of automatic switching apparatus by the application of a marking potential to one of a plurality of marking conductors, marking conductors divided into groups, 110 a register operable in accordance with a digit of a telephone number to select a marking conductor in each of said groups, and a register operated in accordance with a different digit in the telephone number to select a particular one of the marking conductors selected in accordance with the first named digit.

2. In a telephone system wherein automatic switches are guided into connection with a desired subscriber's line by the application of a marking potential to one of a plurality of marking conductors, marking conductors multiplied into the banks of a plurality of switches having access to called lines, 120 two register controllers, means for connecting either of said register controllers to any one of said switches, means including registering apparatus in either register controller for 125 marking a desired one of said marking con- 130

ductors, and means for preventing the marking of a conductor by one register controller at a time when a conductor is marked by the other register controller.

5. 3. In a telephone system, two register controllers, a plurality of connector switches having access to called lines, means for extending a connection from a calling line to one of said connector switches and for rendering one of said register controllers temporarily individual to such connector switch, means controlled over any one of a plurality of marking conductors for operating said connector switch as a finder to find a called line, 10 means including registering apparatus in the register controller set over the calling line to mark one of said conductors, and means for preventing the marking of one of said conductors by one of said register controllers at a 15 time when a conductor is marked by the other register controller.

4. In a telephone system, a trunk line, a plurality of register controllers, means for completing a connection between a calling 20 line and said trunk line and for rendering one of said register controllers temporarily individual to said trunk line, means including registering apparatus in the register controller for recording the number of the desired line and for recording the designation 25 of the desired party on the line in case a party line is called, automatic switching mechanism controlled in accordance with the setting of said registering apparatus to extend a connection from said trunk line to the desired line, and means including a ringing-code generator individual to said register controller to generate and transmit to the called line the particular code of the 30 called party as indicated by the setting of the said registering apparatus.

5. In a party-line telephone system, a code generator comprising a plurality of code-generating devices for generating separate 45 codes corresponding to different parties on a party line, a digit register having access to said code generating devices and arranged to select the same device upon the registration of either of two digits, and means associated with said registering device for making an addition to the selected code automatically when it is set in one of the two said positions.

6. In a party-line telephone system, a code generator comprising a plurality of code-generating devices for generating separate codes corresponding to different parties on a party line, a digit register having access to said code-generating devices and arranged 60 to select the same device upon the registration of either of two digits, and means associated with said registering device for automatically modifying the selected code when it is set in one of said two positions.

65. 7. In an automatic telephone system, an

automatic hunting switch having access to lines, means for extending a connection from a calling line to said switch, means including registering apparatus set over the calling line in accordance with the destination of the call for marking a group of lines accessible to said switch, means for automatically causing said switch to advance to the marked group of lines, and means controlled by the busy or idle condition of the lines within the group for continuing the hunting movement of said switch until an idle line is encountered.

8. In a telephone system, an automatic switch having access to lines, a test contact for each line, a marking contact for each line, means including registering apparatus for marking one of said marking contacts, means for operating said switch into engagement with the marked contact, and means controlled over the associated test contact for continuing the movement of the switch in case the line associated with the marked contact is busy.

9. In a telephone system, a manual switchboard, another switchboard, a line extending between said switchboards, means for setting up a connection over said line through said switchboards and for setting up a current flow over said line, means for breaking down 95 said connection at the said other switchboard, and means thereupon effective for momentarily reversing the current flow over said line.

10. In a telephone system, means including automatic switching apparatus for setting up connections to subscribers' lines responsive to impulses representing the digits in the telephone numbers of said lines, means included in said automatic switching apparatus for denying the connection in case the called line is busy, and means for causing the connection to be completed to a busy line in case a preassigned digit is prefixed to the subscriber's number.

11. In an automatic telephone system, automatic switching apparatus for the common use of operators and calling subscribers to set up connections to called lines, means for denying the connection in case a called line is busy, and means responsive only in case the call is being set up from an operator's switchboard for completing a connection to a busy line responsive to prefixing a preassigned digit to the digits of the telephone number.

12. In a telephone system, a switch controlling device comprising registering apparatus for registering the tens and units digits in called numbers, said registering apparatus having one movement for the tens digit and another movement for the units digit, and means for causing said apparatus to operate twice in its tens digit movement in case the first digit received by such apparatus is a pre-determined digit, the last named means in-

cluding arrangements for automatically releasing said apparatus at the end of the said predetermined digit.

13. In a telephone system, a telephone exchange including automatic switches and register controllers arranged to be set in accordance with desired numbers to control said switches, a line incoming to said exchange, means in said exchange for giving signals indicative of conditions within the exchange, and means including said register controllers for extending the incoming line into association with the last named means, whereby the conditions existing in the exchange may be determined over said line.

14. In a register controller for use in controlling the operation of automatic switches in an automatic telephone exchange, a tens register, a units register, and a party register arranged to be operated to register the tens, units, and party selecting digits in a telephone number, an impulsing circuit over which said registers are operated, means automatically effective for shifting said impulsing circuit from the tens register to the units register and for later switching it from the units register to the party register, and means responsive to said tens register being set in a predetermined position for thereupon switching the impulse circuit directly from the tens register to the party selector.

15. In a telephone system, three registering devices arranged to respond successively to three digits, and means responsive to the setting of the first register in accordance with a predetermined digit for causing the third register to respond to the second digit.

In witness whereof, I hereunto subscribe my name this 25th day of February, A. D. 1930.

CHARLES LEONARD PETERS.
